(57) **CLAIM**

The ornamental design for an applicator for applying a sheet material to a substrate, as shown and described.

DESCRIPTION

FIG. 1 is a perspective view of the applicator for applying a sheet material to a substrate;

FIG. 2 is a top view of the applicator;

FIG. 3 is a rear view of the applicator;

FIG. 4 is a front view of the applicator;

FIG. 5 is a left side view of the applicator, the right side view being the same; and,

FIG. 6 is a bottom view of the applicator.

The broken lines shown in the drawings are for illustrative purposes only and form no part of the claimed design.
